Walter E. Wolheim
ATTORNEY

UNITED STATES PATENT OFFICE.

ALBERT W. MORSE, OF LONG ISLAND CITY, NEW YORK.

OIL BURNER.

Application filed May 17, 1926. Serial No. 109,638.

This invention relates to improvements in oil burners, and is especially adapted for use with the kind known as "natural draft" burners, that is, burners suitable for installation in small boilers or furnaces of the domestic type, in which air is drawn in by the suction in the chimney, although not necessarily limited to this particular type.

10 In devices of this sort, the oil is supplied to the burner under slight pressure, caused either by gravity or a pump, to a hot plate where it vaporizes and mixes with air drawn in through the open door of the ash pit to be passed through a manifold which discharges the air so drawn in over the hot plate to cause combustion. The resulting flame is propagated between the branches of the manifold thereby slightly preheating the air.

15 With burners of this type, however, the one objectionable feature is frequent carbonizing of the burner, that is, the space around the manifold and the walls of the firebox of the furnace or boiler become coated with carbon due to the comparatively cool temperature of the heating surfaces of the boiler and the burner with which the flame comes in contact.

20 I have found by careful experiments that by raising the temperature of the combustion space around the flame and the surfaces with which it contacts, the unconsumed particles of oil which are usually deposited in form of carbon, are entirely consumed, and 25 carbonizing with its subsequent frequent cleaning entirely eliminated.

25 I accomplish this desired result by completely enclosing the burner manifold in the firebox of the furnace with a perforated 30 dome-shaped casing of, preferably, a refractory material, the walls of which are in spaced relation from the walls of the firebox of the boiler and from the manifold, providing effectively a primary combustion 35 chamber for the burner within the firebox which latter may be considered a secondary combustion chamber. By so doing, I increase 40 greatly the temperature around the manifold of the burner which preheats the air drawn in therethrough and discharges it over 45 the hot plate at a much higher degree than heretofore which results in quicker vaporization of the oil. Furthermore, the casing, being of refractory or other suitable material which when heated becomes incandescent, radiates such an amount of heat that

all particles of unconsumed oil, i. e. carbon, are burned up. No carbon escapes through the perforations of the casing after the latter becomes entirely incandescent and the radiant characteristics of which furnish an evenly distributed heat over the entire heating surface of the boiler exposed thereto which is so greatly desired to increase the efficiency of the heating plant.

30 In the accompanying drawings, illustrative of a preferred embodiment of my invention,

Fig. 1 shows a diagrammatic fragmentary vertical sectional view through a heating boiler of the domestic type with a typical burner placed within its firebox and a dome-shaped casing in accordance with the principle of my invention placed over the same; and

Fig. 2 is a horizontal cross sectional view along the plane of line 2—2 in Fig. 1.

Like characters of reference denote similar parts throughout both views.

10 is a boiler or furnace having a firebox 11 and an ashpit 12 provided with a door opening 13. 14 are grate bars. Placed upon the grate bars 14 is a circular base plate 15 of a burner, having four passages 16, preferably, oblong with corners rounded. Fitted into recesses 17 on top of the base 15 is a manifold or housing 18 consisting of four upwardly extending hollow branches 19, shaped in cross section to match the inlets 16 of the base, connected to a top chamber 20 which has a downwardly extending open branch 21 in its center. The base 15 has a bowl-shaped open recess 22 at its top. Screwed into a boss 23 in the center of the recess 22 is a vaporizer or hot plate 24 consisting of a shank 25 and a slightly downwardly slanting circular top 26. 27 are circular grooves in the top 26, and 28 is a central oil passage. Vaporizer 24 is in central alignment with downwardly extending branch 21 of the manifold 18.

29 is an oil pipe nipple connected to the lower side of the base 15 in line with oil passage 28 of the vaporizer and extending into the ashpit 12. 30 is a dish-shaped overflow pan, fastened to the oil pipe nipple 29. 31 is an oil supply pipe led into the ashpit through its door opening 13 and connected to the underside of overflow pan 30 in communication with the nipple 29 and oil passage 28 of the vaporizer. 32 is an overflow nipple screwed into the bottom of base 15

and terminating within the overflow pan 30. Overflow nipple 32 is in communication with bowl-shaped top 22 of the base 15 by a duct 33, the inlet of which is slightly elevated over the bottom of recess 22 at 34. 35 is an overflow pipe connected to overflow pan 30.

The base 15 is laid upon the grate bars of the boiler and fastened thereto in level position by a layer 41 of cement or other suitable material which fills up the space around the burner base and the walls of the firebox 11, completely closing off communication between the firebox and the ashpit.

37 is a casing having upwardly extending circular walls 38 merging into a dome-shaped top 39. 40 are perforations through the casing. Casing 37 is placed upon the layer of cement 41 on the grate bars and completely encloses the manifold 18 of the burner. This casing is shown diagrammatically only as in one piece. In practical use, in order to insert it conveniently into the firebox of the boiler, it may be built up in horizontal zones of several layers with a top placed thereon, or it may be made of radially extending segments, or a combination of both. The material to be used is preferably a refractory composition such as silica carbide, or the like, which becomes incandescent when heated and possesses the desired radiant characteristics. While preferring a refractory material, a metal having similar characteristics may, of course, also be used for the casing.

The operation of the device is, as follows: 35 The vaporizer is heated by oil-soaked wicking placed in the bowl 22 below it or by any other convenient means. An oil supply valve (not shown) is then opened to admit oil under slight pressure to pipe 31, nipple 29, passage 28, onto the top of the vaporizer, filling circular grooves 27. Air is drawn into the branches 19 of the manifold 18 through base openings 16 from the ashpit communicating with the atmosphere and discharged from outlet 21 directly over the vaporizer where it mixes with the oil gases and breaks into a flame which issues out from within the inner sides of the branches 19 through the relatively small spaces between them and entirely 45 develops the manifold, practically filling the entire space between the manifold and the inner wall of the casing 37. Gases of combustion communicate with the chimney through perforations 40 of the casing. If too much oil is fed to the vaporizer, the surplus will overflow into the overflow pan 30 through duct 33 and nipple 32 to actuate the usual form of safety valve (not shown) which automatically reduces or shuts off the supply 55 of oil to the burner.

During operation, the casing 37 becomes incandescent and its radiant heat characteristics raise the temperature within it to an appreciable degree, so that the air drawn into the branches of the manifold is preheated to

a much greater degree than in the usual form of burner not employing this casing. The air being preheated will vaporize the oil much more thoroughly and more quickly and will not chill the top of the vaporizer. In order 70 to impart the maximum amount of heat to the air passing through the manifold, I have shaped the branches of oblong cross section, and reduced the flame outlets between. Because of the high heat within the casing 37, 75 the manifold 18 must be made of a particularly well heat resisting composition, and a refractory material similar to that of the casing may also be very advantageously used. In practice it has been found that the high 80 temperature chamber surrounding the manifold and the high temperature of the casing itself, through perforations of which the flame or its gases must pass, burns up all carbon and results in a clean flame within the 85 chamber. The casing itself, being entirely incandescent, subjects the greatest possible amount of heating surface of the boiler to the action of its radiant heat.

While I have shown, by way of illustration, a burner of the natural draft type using atmospheric air for combustion, I do not wish to limit the application of the casing embodying the principal feature of my invention to burners of such type, but any type 90 burner may be used in which air is forced into it by atmospheric pressure or by blower and which is connected to either a vaporizer, as shown, or to mix with oil or gas discharged from a nozzle, or other source of supply, the 100 principal object being to surround that part of the burner which contains the air passages and the primary combustion chamber of the burner with a high temperature zone confined within a casing having walls possessing 105 radiant characteristics.

Moreover, while the casing surrounding the burner has been illustrated with round perforations, obviously any other form of communication between the burner flame and the chimney may be used, such as an annular slot on top of the dome, for instance, and the term "perforation" should be interpreted in its broadest sense.

Furthermore, while I have shown the casing independently of the manifold of the burner, I do not wish to limit myself to this precise arrangement, but may desire to embody the casing integrally with the manifold.

It is understood that various other changes, in the form, proportion, minor details of construction may be resorted to without departing from the principle or sacrificing any of the invention, as defined in the appended 125 claim.

What I claim as new, is:

The combination with the firebox of a heating boiler, of an oil burner adapted to be placed upon the grate bars of the firebox, 130

said burner having a housing for conducting air to the point of oil discharge, the said housing having air inlets at its bottom and its outlet being adapted to discharge air downwardly, and, resting upon the grate bars, a perforated casing of refractory material around the said housing and in spaced relation to the heating surfaces of the boiler, the

said grate bars between the said housing and heating surfaces being covered to permit air being drawn into the burner through the said housing only. ¹⁰

In testimony whereof I have hereunto set my hand.

ALBERT W. MORSE.
